ROAD MAKING MACHINE

Martin Madsen, Huntington Park, Calif., assignor to Madsen Iron Works, Huntington Park, Calif., a corporation of California

Application January 30, 1937, Serial No. 123,183

14 Claims. (Cl. 94—40)

My invention relates to a power driven device having utility in the construction or reconstruction of road surfaces, and relates in particular to a machine for making roads either from the materials present in the road surface previously existing, or from aggregate or surfacing materials which are obtained from other sources. This application is a continuation in part of my pending application Serial No. 645,499, filed December 3, 1932 for Method of and apparatus for producing mineral aggregate road.

It is an object of the invention to provide a device adapted to be moved substantially continuously along a lane or line of travel defining a road to be constructed or an existing road to be reconstructed, this device having means for picking up road surfacing materials and preparing the same for the formation of a suitable road surface, the materials after such preparation being discharged by the machine upon the surface structure on which the road surface is to be formed. It is an older practice to resurface an existing road surface by scarifying the same and then applying a coat of oil which is either left to soak into the materials which are to constitute the road surface, or a layer of sand or gravel, or both, may be spread over the oil. Roads of this character are not very durable in view of the fact that the bonding effect of the road oil or asphalt does not penetrate deeply. Other methods of road surfacing or road construction include the mixing of aggregate or surfacing materials at a plant situated at a more or less distance from the place of road construction, and the subsequent step of spreading the mixture or asphalt and aggregate material so that it may be rolled down to a finished road surface. My present invention provides a device which may be driven slowly along the road, or along the line or lane to be occupied by a road, this device having a mill into which surfacing materials picked up from the road are delivered so as to be therein mixed with a binder such as heavy road oil or asphalt and subsequently discharged at the rear of or behind the device as it moves along and in such position that it may be readily spread and rolled, as the case may be, to produce a road structure of relatively durable character, at a minimum cost and with a minimum expenditure of time, as compared to existing methods of road construction and reconstruction. The surfacing materials which are taken into the mixer may be obtained in several different ways. They may be produced by scarifying the surface of a road which is to be refinished,

so as to break up the materials constituting such road surface, or the materials may be brought from other locations and placed in continuous ridge-like mounds or windrows along the lane which is to be traversed by my device. Regardless of the source of the materials, which may be produced in the manner suggested in the foregoing sentence, such materials are taken into the device as it moves continuously along, are mixed with a suitable binder, preferably a road oil or asphalt, and after being thoroughly mixed with the binder are discharged so as to leave behind the device, and along the lane of travel thereof, a continuous supply of road surfacing material in condition to be spread and rolled. In one practice of my method of road construction, the existing roadway may be scarified so as to break the surface materials thereof into relatively small pieces, and to the aggregate material thereby produced other materials such as sand, gravel or crushed rock may be added so that a more durable character of road surfacing material is produced. The aggregate mass of material, consisting of the divided surface materials of the previously existing road structure and the added sand, gravel or crushed rock are then formed into continuous ridge-like piles in substantially centralized position relative to the line of travel along which the device is to be driven. It is an object of my invention to provide, for receiving the aggregate materials as they are continuously picked up from the road surface, a mill having an effective, yet simple mixing means therein and means for delivering the binder to the materials just prior to or during the time they are being mixed; it being a further object of the invention to provide a simple and effective means for controlling the mixing action, this means operating to maintain the materials in the mixture for such length of time and under such back pressure that a proper mixing and preparation thereof is assured.

It is a further object of the invention to provide a device of this character having ground engaging elements on the two sides thereof, and means for adjustably and controllably supporting a member for picking up the materials from the road surface, this supporting means having or embodying an automatic device for compensation or independent vertical movement of the ground engaging element, so that tipping of the member for picking up the materials of the road surface will be minimized.

It is a further object of the invention to provide a pick-up means, for taking the material from the ground surface and delivering the same

into the mill, this pick-up means having a hydraulic device for maintaining and controlling the position thereof, this hydraulic device having a pump member continuously pumping a supply of hydraulic fluid such as oil through a bypass, together with a control means for diverting the hydraulic fluid into the hydraulic chambers of the device, or releasing hydraulic fluid from such chambers, as may be desired by the operator of the road making machine.

It is a further object of the invention to provide a road making device of the general character hereinbefore described having adjustable guide means disposed at the forward end thereof for directing the aggregate material into the pick-up means which is adapted to deliver such material into the mill, the adjustability of this guide means making it possible to adapt the same to the various conditions of operation which may be encountered, and assuring that the aggregate materials will be always directed properly into the pick-up means of the road making device.

It is a further object of the invention to provide, in conjunction with the road making device, an improved means for feeding a binder to the materials which are to be mixed or which are being mixed in the mill. This improved binder means is so constructed that it will continuously feed the binder material as the road making device is propelled forwardly and will automatically vary the quantity of binder material in accordance with the change in speed of travel of the road making device. In addition to the foregoing it is an object of the invention to provide a binder feeding device having means whereby it may be adjusted so as to vary the quantity of binder material fed, while the road making device is in operation. For example, as the device is propelled forwardly the operator may observe that the sizes of the windrows of divided material change from time to time, and, without stopping the road making device, they vary the rate of speed of binder material in accordance with the rate at which the aggregate materials are fed into the mixer.

Further objects and advantages of the invention will be brought out in the following specification.

Referring to the drawings which are for illustrative purposes only:

Referring to Figs. 1 to 4 of the drawings, the preferred embodiment of my invention disclosed therein includes a vehicle 15, preferably of automotive type. This vehicle 15 embodies a body structure 16 including a longitudinal frame 17 which may be fabricated from steel structural shape and preferably includes a pair of spaced I-beams 18 which extend forwardly and rearwardly and slope downwardly at a slight angle in forward direction.

The vehicle 15 is provided with ground engaging means of movable or drivable character, such for example as wheels. Such ground engaging means are broadly referred to as tread elements 19 and are preferably of the general character of treads employed on caterpillar type tractors. The tread elements 19 are disposed at the sides of the body structure 16, and lie in vertical planes 20 disposed to the sides of the longitudinal beams 18 of the frame 17 which forms the bed or supporting element of the body structure 16. Each of the tread elements 19 includes a forward wheel 20 and a rearward wheel 21, supported at forward and rearward ends, respectively, of tread frame 22, as that shown in Fig. 1. Although these wheels 20 and 21 might be permitted to run in direct engagement with the ground or road surface, it is preferable that they shall be made of such character that a continuous belt or chain 23, of the form ordinarily employed in caterpillar type of construction, may be mounted on each pair of wheels consisting of a forward wheel 20 and a rearward wheel 21. To drive the tread belt 23, the rearward wheel 21 is provided with sprocket teeth, and teeth are provided for driving both the rear wheels 21 so that they in turn may drive the belt 23, whereby to propel the vehicle 15.

The rearward part of the body structure 16 has a pair of oppositely extending shafts 24 such as shown in Fig. 1, these shafts 24 rotatably supporting the rearward wheels 21 of the tread element 19, and likewise supporting the rearward ends of the tread frame 22, the forward ends of the tread frames and likewise the forward ends of the tread elements 19 being permitted to swing in vertical plane in accordance with accepted caterpillar tractor design. It will be understood that as the forward portions of the tread elements 19 pass over uneven road surfaces, they may move upwardly or downwardly in accordance with the surfaces over which they pass. As shown in Fig. 2, each rear wheel 21 may have a sprocket 25 secured thereto in concentric relation to the shaft member 24 on which each wheel 21 is supported, these sprockets 25 being adapted to engagement by drive chains 26 whereby the wheel 21 and the tread belt 23 may be driven, means being provided, as will be later described herein, for driving these chains 26 at different speeds as may be required for steering of the vehicle, the same being under the control of the operator as the device is propelled along the line of travel defining or being defined by the position of a road to be formed or reformed.

The intermediate portion of the body structure 16 includes an engine housing 27 to contain an

engine 28, preferably of internal combustion type, the rearward end 29 of which is shown in Figs. 1 and 4 projecting from the rearward end of the engine housing 27 so that drive means 5 may be connected thereto.

As shown in Fig. 1 the rearward or leftward portion of the frame 17 of the body structure 16 includes a platform structure 31 having a pair of structural channels 32 which are tied together by cross-bracing means 33, this platform structure carrying an engine 34 which is mounted in laterally disposed relation and has a variable speed transmission 35, best shown in Fig. 2, which connects to a shaft 36 with a variable speed and controllable tractor drive and steering mechanism 37 which is shown only in elevation for the reason that it is of the type ordinarily employed in tractor design and is merely adapted to the needs of the present device. In cooperating relation to the tractor drive and steering mechanism 37 an operator's platform 38 is mounted, this platform having a seat 39 which is offset leftwardly with relation to the vehicle 15 so that an operator seated thereon may readily see down the roadway ahead of the vehicle. The operator's platform 38 has lever and pedal means 40 and 41 thereon adapted to be moved by the operator so as to control the vehicle 15. On a sub-platform 43 which projects rightwardly from the frame 17 of the vehicle body 18, a feed pump 44 is mounted in such position that it may be driven from the engine 34, as will be hereinafter described.

As best shown in Figs. 3 and 8, structural angles 45 are secured to the lower faces of the I-beams 18 and have the purpose of connecting to the frame 17 a bowl 46 forming part of a mixing mill 47. The bowl 46 includes a lower metal plate 48 having a bottom wall 49, the longitudinal edge 49 portions of which curve upwardly and verge with vertical side walls 50 which are connected to the downwardly extending legs of the angles 45. By means of screws 51, a ridge bar 52 is secured longitudinally and centrally in the bottom of the 45 bowl 46. The front edge portion 53 of the plate 48 which forms the bowl 46 is deformed in shape from its rounded effect shown as 54 to a shape wherein a horizontal scraper or knife support 55 and a vertical wall portion 56 are provided. From the vertical wall portions 56 vertical plates or aprons 57 are extended forwardly so as to form a mixing or earth loosening chamber 59, in front of the knife or scraper blade 58, the bottom of 50 which is open, or as otherwise stated, the bottom 55 of which is formed by the ground or road surface lying between the lower edges of the apron 57. The lower edges 57a of the aprons or walls 57 are formed horizontally as shown and have adjustable shoes 57b. The 20 end wall 60 is dis-

As best shown in Fig. 8, an end wall 60 is disposed across the upper portion of the rearward end of the bowl 46, and the lower portion of the wall or plate 48 of the bowl 46 is provided with a notch 61 so as to form a discharge opening for the rearward end of the mixing mill 47. A feature of the invention is to provide a means for producing a continuous back pressure against the discharge of mixed materials from the bowl 46, regardless of whether the quantity of materials fed into the bowl is small or large, this back pressure being controllable so that the materials being mixed in the mill will be caused to pile up or accumulate in the rearward portion thereof, and such materials will be thereby held in the

mill for a sufficient length of time and under sufficient pressure to accomplish the desired mixing thereof. This automatic and adjustable means for exerting a back pressure upon the discharging materials I show in the form of a plate or door 63, connected by means of a horizontal hinge 64 to the lower edge of the end wall 60, and having a rearwardly extending arm 65 on which an adjustable weight 66 is mounted so as to produce a static force tending to hold the door 63 in the closed position in which it is shown in full line in Fig. 8.

The mixing mill 47 has mixing means consisting of paddles 67 which are mounted on longitudinal and substantially parallel shafts 68 supported by a rear bearing means 69 disposed to the rear of the wall 60, and by a forward bearing means 70 supported by means of brackets 71 in positions spaced forwardly of the blade 58 and within the forward portion of the chamber 59 defined by the aprons 57 so that loosening blades 72 may be mounted on the shafts 68 within the chamber 59 and ahead of the blade 58, so that these loosening blades 72 may operate to loosen up the road materials which lie in the path of movement of the blade 58, before the blade 58 reaches the same, thereby materially facilitating the ease with which the pick-up means represented by the blade 58 and the mouth portion 53 of the bowl 46 may pick up these road materials and direct the same into the mill 47. The shafts 68 are rotated by the engine 27 through a train of gears 68a.

In accordance with my co-pending application 35
hereinbefore mentioned, the blades 67 on each of the shafts 68 move upwardly in the center of the bowl 46. In other words, the left-hand shaft, looking at Fig. 3, rotates in anti-clockwise direction, and the right-hand shaft in this figure rotates in clockwise direction. As clearly shown in Fig. 8, the blades 67 are sloped to force the materials which have entered the bowl 46 rearwardly toward the outlet opening 62, while at the same time thoroughly mixing these materials with an asphalt material, such, for example, as heavy road oil, adapted to be fed to the materials to be mixed through an oil discharge member 74 disposed toward the forward end of the mixing bowl 47. 45

The oil to be mixed with the aggregate materials in mixing mill 47 is preferably received from a tank wagon which is pulled along behind the road making device disclosed herein, and it is a feature of the present invention to provide a means whereby the feeding of the binder to the aggregate through delivery means, such, as the member 14, may be accurately and automatically controlled. For this purpose I have provided the oil feed pump 44 which is of the reciprocating and plunger type and preferably has two pistons as shown working in alternate relation. As shown in Fig. 4, this feed pump 44 has an oil inlet means 75 to which may be connected a hose 76 which extends rearwardly from the vehicle 15 to a tank wagon which is pulled along behind the vehicle, this tank wagon having means for heating the oil or asphalt if the same is required by the characteristics of the binder being employed. In some uses of my invention the binder employed may be a road oil which will flow readily at normal temperatures; whereas, other uses of my device may require a relatively heavy asphalt which will require heating.

The feed pump 44 has a pair of pistons 77 from 75

which piston rods 78 project forwardly to cross-heads 79 to which walking beams or fulcrum levers 80 are connected by pivot means 81 in positions to extend upwardly. Pivots 82 at the upper 5 end of the fulcrum levers 80 are connected to connecting rods 83, the leftward or rearward ends of which engage the crank 84 of the laterally extending crank shaft 85 supported in bearings 86, this crank shaft 85 being driven by the engine 10 10 34 through a shaft 87 and the reduction gear means 88, the shaft 87 being connected through a universal coupling 89 with the transmission means 90 which is driven by the engine 34 through the shaft 86. Intermediate the ends thereof of the 15 fulcrum levers 80 are engaged by vertically adjustable pivots or fulcrum means 91 which, as shown in Fig. 10, comprise a vertically movable block 92 carried in a vertical slide 93 and having a vertical threaded opening 94 through which 20 an adjustment screw 95 passes. The block 92 has a pair of oppositely extending trunnions 96 to serve as pivots on which bodies 97 are turnable, the trunnions 96 having annular channels 98 therein engaged by screws 99 which project 25 inwardly from the walls of the bodies 97 to prevent the bodies 97 from moving outwardly on the trunnions 96. Each of the bodies 97 has a channel or opening 100 of rectangular cross-section in the outer portion thereof, and through 30 each of these channels 100 a fulcrum lever 80 passes, as clearly shown in Fig. 10. Each body 97 forms a means for pivotally connecting the intermediate portion of a fulcrum lever 80 with a trunnion 96. When the crank shaft 85 is rotated, and reciprocation is transmitted through the connecting rods 83 to the upper ends of the fulcrum levers 80, these levers will be caused to swing on axes defined intermediate the ends 35 thereof by the trunnions 96. Accordingly, if the trunnions 96 are positioned intermediate the lower and upper pivots 81 and 82 of the fulcrum levers 80, the cross-heads 79 and the pistons 77 associated therewith will be reciprocated back and forth the same distance as the upper ends 40 of the fulcrum levers 80. But, should the block 92 of the fulcrum means 90 be raised or lowered, the movement of the pistons 77 of the pump 44 will be respectively increased and decreased owing 45 to the shift of the fulcrum points on which the fulcrum levers 80 swing. As previously herein indicated the block 92 of the fulcrum means 90 may be raised or lowered by means of the adjustment screw 95 which is under control of the operator occupying the rear platform of the 50 vehicle 15.

The rearward part of the longitudinal frame 17 is pivotally supported around the shafts 24 which support the wheels 21. The rearward part 55 of this frame, therefore, is non-adjustable in height. In order that the mixing mill 47 may pick up the road material in front of the blade 58 it is necessary that this mixing mill slope downwardly and forwardly so that the blade 58 is in proper position with respect to the road 60 surface. In view of the fact that the mixing mill in the form of my invention shown herein is rigidly secured to the longitudinal frame 17, it is necessary to provide a means whereby the forward part of the longitudinal frame is vertically 65 adjustable. This means I provide in the form of a hydraulic means or hydraulic mechanism whereby an operator may raise or lower the forward end of the longitudinal frame 17 and also 70 the forward end of the mixing mill 47 in order to 75

properly position the blade 58. Also incorporated in the hydraulic means is an equalizing means so that in the event an obstruction rides under one of the caterpillar treads there will be but a minimum disturbance to the proper operating position of the blade 58. 5

As shown best in Figs. 1, 3, 4, and 11, this portion of my invention provides a pair of hydraulic piston and cylinder means 105, one of which is associated with the forward part of each tread frame 22 and one of the I-beams 18. Mounted at the forward end of each tread frame 22 are brackets 106 to which upwardly extending arms 107 are pivotally connected, the pairs of arms 107 being pivotally connected to a cross-bar 108. 10 Pivot to the central part of each cross-bar 108 is a block 109 to which a clevice 110 is also pivotally connected, these parts 109 and 110 constituting a universal joint. Extended upwardly from each clevice 110 is a piston rod 112 having 15 a piston 113 secured to the upper end thereof, each piston 113 being positioned in a hydraulic cylinder 114. Each cylinder 114 is rigidly mounted on a cross-beam 116 which, as shown in Figs. 1, 3, and 4, is supported by the I-beams 18 through the medium of interposed channels 20 25 117.

Connected to the upper part of each of the hydraulic cylinders 114 is a liquid conveying pipe 30 119 whereby liquid or fluid under pressure is delivered to the upper end of each of the hydraulic cylinders 114. The delivery of liquid under pressure to the pipe 119 serves to raise the cylinders 114 relative to the pistons 113, thus raising the forward part of the longitudinal frame 17 and raising along with it the forward part of the mixing mill 47, this movement taking place around the shaft 24 as a center of rotation. When liquid is removed from the cylinders 114 the frame is lowered and the forward part of the 40 frame and mixing mill move downward toward the ground, thus bringing the blade 58 closer to the road surface. 35

As shown best in Figs. 3 and 11, my invention provides a liquid pump 120 which is mounted so as to be operated by the engine 34 at the rear of the road pug. This pump 120 draws liquid through a pipe 121 from a liquid sump 122 which is conveniently located on the apparatus adjacent the pump 120. Liquid under pressure is delivered by the pump 120 through a pipe 123. The pipe 123 is connected to a control valve 124 mounted on the forward platform 125 which is positioned directly ahead of the engine housing 55 21. The valve 124 has a valve body 126 providing a chamber 127 in which a valve member 128 is operable, this valve member 128 being operated by a lever 129 accessible to an operator working on the platform 125. The valve body 126 has 60 four communicating ports 130, 131, 132, and 133. The liquid pipe 123 is connected to the port 130, and the liquid pipe 112 which is connected to the upper end of each of the hydraulic cylinders 114 is connected by means of a branch pipe 134 to the port 131. A return pipe 135 is connected to the port 132 and extends to the sump 122, while a return pipe 136 is connected to the port 133 and extends to the sump 122. The valve member 128 is designed so that it has a diametral web 137 having closure formations 138 formed thereon, and connected to the diametral web 137 is a tubular member 140 which extends to the inner cylindrical wall of the body 126 and forms 70 75 75

a sealing engagement therewith, this tubular member 140 having a passage 141.

In the operation of the apparatus under description, when the operating lever is in the position shown in full lines in Fig. 3 the valve member 128 is positioned as shown in Fig. 7. The pump 120 is continuously operated so that there is at all times a flow of liquid from the sump 122 through the pipe 121 to the pump 120, and from the pump 120 through the pipe 123 to the valve 124. When the parts are positioned as shown this liquid may flow through the passage 141, the port 132, and be returned to the sump 122 through the return pipe 135. At this time the pipe 119 is closed and the hydraulic system may be considered as locked. In other words, whatever fluid is in the pump 119 and in the upper ends of the hydraulic cylinders 114 remains in these parts, and additional liquid cannot flow into the system, nor can any of the liquid flow out of the system.

When the operator desires to raise the forward part of the frame and the mixing mill, such as he may desire to do to accommodate irregularities of the road, the operating lever 129 is moved in a clockwise direction, as shown in Fig. 3, which moves the valve member 128 into a position indicated by dotted lines 145 of Fig. 11. This, it will be seen, moves the passage 141 from communication with the port 132 and prevents escape of liquid therethrough. At the same time it connects the port 131 with the port 130 and the pump 120 therefore pump liquid through the pipe 134 into the pipe 119 and delivers liquid to the hydraulic cylinders 114.

When the operator desires to lower the forward part of the longitudinal frame and the forward part of the mixing mill the lever 129 is moved in an anti-clockwise direction in order to move the valve member 128 into a position which will communicate the port 131 with the port 132. This allows liquid to flow from the pipe 119 through the pipe 134, through the valve 24, and the return pipe 135 to the sump 122. In view of the fact that the pump 120 is continuously operating, it is necessary that a means be provided for at this time returning the pumped liquid to the sump 122. When the valve is in the position to communicate the port 131 and the port 132 the port 130 is in communication with the port 133, and therefore the pumped liquid will pass through the port 133, the return pipe 136, to the sump 122.

For the purpose of controlling the rate of lowering of the forward part of the longitudinal frame 117 and the forward part of the mixing mill 47 I provide a check means in the form of a check valve 150 which has a valve member or ball 151 which is removed from its seat 152 when the liquid is flowing into the pipe 119. In other words, the flow of liquid into the pipe 119 is unrestricted. However, a reverse flow through the check valve 150 seats the valve 151, but I provide a passage 153 closed by an adjustable needle 154 which may be opened to provide a slow reverse flow of liquid through this opening 153. This device is a precautionary means to prevent a sudden lowering of the apparatus when the valve is moved into a position to communicate the port 131 with the port 132.

The hydraulic mechanism just described, in addition to performing the usual functions of raising and lowering the forward parts of the apparatus in order to properly position the blade 58, also acts as an equalizing means so that in the

event one of the treads runs over an obstruction or is in some manner raised from normal position there will be but a minimum of disturbance to the proper operating position of the blade 58. As previously pointed out, the rearward part 5 of the longitudinal frame 17 is supported on the shaft 24 which supports the wheels 21. With the wheels 21 in proper position with respect to the road, the mixing bowl is also in a proper horizontal transverse operating position with respect to the road, and the only additional adjustment which is necessary is to raise or lower the blade 58 to a suitable position, this latter function being performed by the hydraulic mechanism just described. The forward wheels 20, 15 10 however, may raise or lower relative to the rear wheels 21, this being possible since the front wheels are supported by the tread frames 22 which are free to raise vertically. When the forward wheel or the forward part of the caterpillar tread rides onto an obstruction the tread frame 22 will pivot around the axis of rotation of the gear wheel 120. If there were a rigid connection between the forward part of the longitudinal frame 17 and the forward part of the 25 tread frame 22, the result would be that the frame 17 would be tilted from proper transverse, horizontal position, and one end of the blade 58 would be raised relative to the other. However, in view of the hydraulic connection between the parts, the forward part of the tread frame which has been raised may raise independently of the longitudinal frame. When this occurs liquid under pressure is forced out of the hydraulic cylinder positioned thereabove, and this 30 liquid flows through the pipe 119 to the hydraulic cylinder at the opposite side of the apparatus. This, as is apparent, produces a slight raising of the forward part of the frame and after the obstruction is removed the parts automatically and immediately return to normal operating positions. However, due to the hydraulic connection the mixing mill is not tilted from its proper operating position, and the only abnormal position which is produced is the slight raising 35 or lowering of the blade 58.

As illustrated in Figs. 1, 5, 6 and 7, my invention provides mold boards 160 which are mounted at the front end of the mixing mill and serve to gather the loose materials, and, as will later be explained, are adjustable as to swath, height, and scraping angle. The mold boards 160 and each of the supporting means are identical in construction except that one is right-hand and the other is left-hand, and therefore only one 55 of them will be described in detail. Mounted at the forward part of each apron 57 is a mounting bracket 161 having a plurality of lugs 162 through which a rotatable adjusting screw 163 is extended. Threadedly mounted on the screw 163 is a 60 nut 164 to which a pivot shaft 165 is pivotally connected on a transverse horizontal plane as indicated at 166. The pivot shaft 165 extends through a bracket 167 secured to the outer side of the related mold board 160. The mold board 65 160 may rotate around the shaft 165 as its center and may also swing around the pivot 166.

Pivoted to swing in a horizontal plane on the upper part of the shaft 163 is a forwardly extending arm 170. Mounted on the forward end 70 of the arm 170 is a vertical cylinder 171 into which there is extended from the lower end thereof a sleeve 172. The upper part of the sleeve 172 is provided in the form of a nut 173 into which an adjustment screw 174 is threaded. 75

- The upper end of the adjustment screw 174 extends to the exterior of the cylinder 171 and is provided with a wrench receiving portion 175 and also with an enlargement or collar 176 which 5 engages the outer wall of a removable closure plate 177. Compressed between the closure plate 177 and the nut portion 173 of the sleeve 172 is a spring 178 conveniently located within the cylinder 171 as shown. By rotating the screw 174 10 the sleeve may be raised or lowered. Likewise, if a force is applied to the sleeve tending to raise it, and if this force is sufficient to overcome the force of the spring 178, the sleeve and also the adjustment screw 174 may be bodily raised. The 15 purpose of this function will be pointed out in the following description.

The lower end of the sleeve 172 is connected by a pivot pin 180 to a bracket 181 which has a depending lug 182, which is in turn connected 20 by a pivot 183 to a connection member 184 secured to the mold board 160. Extending upwardly from the bracket 181 and forming a part thereof is an arm 186 and secured to the mold board 25 is an arm member 187 having a horizontally elongated slot 188, the arms 186 and 187 being secured together by means of a bolt 189.

- By rotating the adjustment screw 174 to raise or lower the sleeve 172 the mold board 160 may be swung around the pivot 166. In other words, 30 the forward part of the mold board may be raised or lowered. By loosening the bolt 189, the mold board may be swung on the pivot 183 and in this way a pivoting of the mold board around the shaft 164 and the pivot 183 may be accomplished. In addition to the adjustment just referred to, the mold board may be swung around a vertical pivot corresponding to the center of the vertical adjusting screw 163, and this is accomplished by means shown best in Figs. 5 and 6. 35 Secured to the forward part of the longitudinal frame is a cross-member 192 having secured to the outer ends thereof an arcuate rack 193, there being one rack for each mold board construction. Each rack 193 is arcuated around one of the vertical adjusting shafts 165 as its center. 40 For the purpose of supporting the forward end of the arms 170 my invention provides a bearing member 194 which, as shown in Fig. 6, is removably secured to the arm 170, such as by a machine screw 195, and which extends over a lower flange 196 of the member 192. This provides 45 means whereby the arm may be swung on its pivot but at the same time supported so as not to place too great a strain on the bearing connection between the arm 170 and the vertical adjusting screw 163. Supported by the forward part of the arm 170 are bearings 197 supporting a shaft 198 carrying a worm 199 which engages with the arcuate rack 193. The end of the shaft 198 is designed to accommodate a wrench whereby the worm 199 may be rotated in order to 50 swing the arms around their pivots. In this way the entire mold board construction may be moved from a position extending outward as shown in Fig. 5 into a position extending substantially straight forward.

The mold board construction is so designed that it may be extended outwardly to provide the desired swath and so that the mold boards may also be raised, or lowered, or properly angled to accommodate any slope, crown, or curvature of road bed.

One of the features of the mold board construction, in addition to those just enumerated, is the fact that the forward part of the mold board may be raised bodily by compressing the

spring 178, and this acts as a precautionary measure in the event some obstruction rides under the mold board. The various adjusting means are conveniently located and the operator may very readily and satisfactorily adjust the mold boards 160 to such positions that all of the road material may be directed into the mixing mill and therein mixed with the road oil.

From the foregoing description it is believed that the operation of the apparatus of my invention and the method by which it performs its work will be readily understood. A brief description of its operation is substantially as follows.

The operator may first place the apparatus 15 on the road where the material is to be picked up and mixed with road oil. The mixing mill is then adjusted in height so that the blade 58 occupies a proper position relative to the road surface, this being done by proper operation of the 20 lever 129 by the operator who is positioned on the platform 125. Also the mold boards 160 are properly positioned with respect to the road bed, being extended outwardly to cover the proper width, and being adjusted laterally and horizontally in order that the mold boards may fit the curvature or crown of the road bed or to extend horizontally in the event that there is no crown to the road bed. The feed pump 44 may also be adjusted to deliver approximately the 30 volume of oil required, whereafter the apparatus is put into operation. The operator at the rear of the apparatus handles the controls for both of the engines, clutches, brakes, the mixing pump for the road oil, and various other operations to 35 be performed at that position. The operator on the platform 125 watches the oncoming road bed and windrow for irregularities and manipulates the hydraulic raising and lowering mechanism in order to keep the mold board and blade 40 at their proper height. He may also watch the oil flow and mixer feed condition and also give signals to the rear operator regarding speed and steering.

As the apparatus moves forwardly the mold boards direct the material into the forward compartment or mixing chamber 59 where it is engaged by the paddles 72. These paddles 72 tend to loosen the earth and to force it rearwardly over the blade 58. As the material passes over the blade 58 it is moved rearwardly not only by the material which follows it but also by paddles positioned along the shaft 68. At this time the feed pump 44 delivers road oil through the oil discharge 14 which drops onto the material being mixed by the paddles 72 at a point along the central longitudinal plane of the mixing mill. As the material passes rearwardly through the mixing mill it is continued to be mixed by the paddles 67, and, upon reaching the outlet opening 62, is thoroughly mixed.

I have found that it is quite essential to build up a back pressure on the material being mixed, in order that inter-granular friction within the surfacing may be produced, and I therefore provide an opening 62 designed to accommodate a minimum amount of material passing through the apparatus. As the material accumulates a back pressure is built up which, if it exceeds a predetermined value, forces the door 63 open, 70 against the action of the weights 6. This places a back pressure on the material which is being mixed but at the same time provides a means whereby the apparatus will not be jammed or made inoperative due to the accumulation of too 75

great a load. As the pressure increases the door 63 is gradually opened so that as material enters the mixing mill in larger amounts and the volume in the mill increases, larger amounts may be 5 discharged through the opening 62. As the material entering the mixing mill decreases the door 63 will return toward closed position, and the operation will be entirely automatic. In this way I am able to keep a suitable back pressure on 10 the material regardless of the amount of material passing through the apparatus, and in this way the important advantages resulting from back pressure may be obtained even though the capacity varies materially.

15 The mixing action is the same as that which is produced in the mixing mill of my copending application referred to heretofore, the important advantage in the present construction being the maintaining of back pressure on the material 20 being mixed even though the material is being passed through the mixing bowl in relatively small or relatively large amounts. As pointed out heretofore, the feed pump 44 is operated by the engine 34 which drives the apparatus, and therefore its operation is correlated therewith. Should 25 more or less oil be required, the pump may be conveniently adjusted while the apparatus is in operation merely by rotating the adjustment screw 95, which has the effect of changing the 30 lengths of the fulcrum levers 80.

During the moving of the apparatus along the road bed the operator on the platform 125 raises and lowers the forward part of the longitudinal frame in order to properly position the mold 35 boards and the blade. Should the forward part of either of the caterpillar treads be raised or lowered from normal operating position, the hydraulic means will compensate for this change in position, as previously pointed out.

40 I believe my invention to be broadly new and recognize that various alterations and modifications may be made without departing from the spirit and scope of my invention. I therefore do not wish my claims to be construed to limit 45 the details of construction illustrated herein, but wish my invention to be broadly construed in accordance with the appended claims and to cover broadly the invention in its entirety as well as the several sub-combinations and elements 50 which comprise the whole.

I claim as my invention:

1. In a road making machine of the class described, the combination of: a vehicle having rollable ground engaging means whereby the vehicle 55 is movably supported on a supporting surface; a mixing mill carried by said vehicle having a material gathering blade, the mixing mill rearwardly of said blade having a bottom wall and side walls, and having side walls extending forwardly of said blade; shoes connected to the lower edges of said side walls so as to be adjusted vertically relative to the road surface 60 traversed by said road making machine; and mold boards adjustably mounted ahead of said side walls.

2. In a road making machine of the class described, the combination of: a vehicle having rollable ground engaging means whereby the vehicle 70 is movably supported on a supporting surface; a mixing mill carried by said vehicle having material mixing means therein, a blade for gathering from the surface material to be mixed, and discharging means for delivering mixed material to the surface; confining walls forming a 75 chamber ahead of said mixing mill; shoes con-

nected to the lower edges of said confining walls so as to be adjustable vertically relative to the road surface over which said road making machine is driven; and a plurality of independent paddles operable in said chamber and above said 5 blade.

3. In a road making machine of the class described, the combination of: a vehicle having rollable ground engaging means whereby the vehicle is movably supported on a supporting surface; a mixing mill carried by said vehicle having material mixing means therein, a blade for gathering from the surface material to be mixed, and discharge means for delivering mixed material to the surface; and adjustable means operable in response to the pressure of the material in said mixing mill for holding back the movement of said material adjacent said discharge means.

4. In a road making machine of the class described, the combination of: a vehicle having rollable ground engaging means whereby the vehicle is movably supported on a supporting surface; a mixing mill carried by said vehicle having material mixing means therein, a blade for gathering from the surface material to be mixed, and a discharge opening at the rearward end of said mixing mill for delivering mixed material from said mixing mill; and adjustable back pressure means operable in response to the pressure 30 of the material in said mixing mill operatively associated with said discharge opening.

5. In a road making machine of the class described, the combination of: a vehicle having rollable ground engaging means whereby the vehicle is movably supported on a supporting surface; a mixing mill carried by said vehicle having material mixing means therein, a blade for gathering from the surface material to be mixed, and a discharge opening at the rearward end of 40 said mixing mill for delivering mixed material from said mixing mill; a movable closure means for said discharge opening; and yieldable pressure applying means for holding said closure means in closed position.

6. In a road making machine of the class described, the combination of: a vehicle including a pair of rear wheel means and a pair of front wheel means; a mixing mill carried by said vehicle and pivotally supported near said rear wheel means; a pair of hydraulic lifting means, one being operatively connected between each of said front wheel means and said mixing mill; and connecting means for connecting the cylinders of said hydraulic lifting means to provide 55 equal fluid pressure in each.

7. In a road making machine of the class described, the combination of: a vehicle including a pair of rear wheel means and a pair of front wheel means; a mixing mill carried by said vehicle and pivotally supported near said rear wheel means; a pair of hydraulic lifting means, one being operatively connected between each of said front wheel means and said mixing mill; connecting means for connecting the cylinders 65 of said hydraulic lifting means to provide equal fluid pressure in each; and fluid control means for delivering or withdrawing fluid to or from said hydraulic lifting means.

8. In a road making machine of the class described, the combination of: a vehicle adapted to be movably supported on a surface; a mixing mill supported by said vehicle having a blade adapted to gather material from said surface; and mold boards supported at the forward end 75

of said mixing mill and being adjustably connected thereto for bodily and angular relative movement to conform to the contour of said surface and to vary the swath of said apparatus.

9. In a mold board construction, for use as disclosed, the combination of: a supporting structure; a mold board; rear connection means for pivotally connecting the rear part of said mold board to said supporting structure, and for rais-

10. ing or lowering same; and front connection means for connecting said mold board to said supporting structure for raising or lowering same or for pivoting same in a longitudinal plane.

10. In a mold board construction, for use as disclosed, the combination of: a supporting structure; a mold board; rear connection means for pivotally connecting the rear part of said mold board to said supporting structure, and for raising or lowering same; front connection means for connecting said mold board to said supporting structure for raising or lowering same or for pivoting same in a longitudinal plane; and means for laterally moving said front connection means.

11. In a road making machine of the character described, the combination of: a vehicle adapted to move along a road surface; a mixing mill carried by said vehicle to receive, mix, and discharge road material; means for supplying a binder to the road material, said supplying means including a positive displacement pump having a drive means which is variable in its operation; movable means having connection with a ground engaging part of said vehicle so as to move in accordance with the rate of travel of said vehicle along said road surface; and an operative connection between said drive means and said movable means and acting to vary the operation of said drive means so that the feeding of binder to said road material will vary in accordance with the rate of travel of said vehicle.

12. In a road making machine of the charac-

ter described, the combination of: a vehicle adapted to move along a road surface; a mixing mill carried by said vehicle to receive, mix, and discharge road material; means for supplying a binder to the road material, said supplying means including a pump having a moving wall to displace the binder; and means for varying the movement of said moving wall of said pump in accordance with the variation of the rate of travel of said vehicle along said road surface.

13. In a road making machine of the character described, the combination of: a vehicle adapted to move along a road surface; a mixing mill carried by said vehicle to receive, mix, and discharge road material; means for supplying a binder to the road material; means for propelling said vehicle over said surface; a moving part which varies in movement in accordance with the rate of travel of said vehicle; a flow controlling connection between the said moving part and said supplying means operating to vary the supplying action of said supplying means in proportion to the rate of travel of said vehicle; and means varying the action of said supplying means independently of the travel of said vehicle.

14. In a road making machine of the character described, the combination of: a vehicle adapted to move along a road surface; a mixing mill carried by said vehicle to receive, mix, and discharge road material; means for supplying a binder to the road material, said supplying means including a pump having a moving wall to displace the binder, means for varying the movement of said moving wall of said pump in accordance with the variation of the rate of travel of said vehicle along said road surface; and means varying the movement of said moving wall of said pump independently of the rate of travel of said vehicle.

MARTIN MADSEN. 40

CERTIFICATE OF CORRECTION.

Patent No. 2,211,933.

August 20, 1940.

MARTIN MADSEN.

It is hereby certified that error appears in the printed specification of the above numbered patent requiring correction as follows: Page 6, second column, line 71, for "weights 6" read --weights 66--; page 7, first column, line 73, claim 2, for the word "discharging" read --discharge--; and second column, line 11, claim 3, for "fill" read --mill--; and that the said Letters Patent should be read with this correction therein that the same may conform to the record of the case in the Patent Office.

Signed and sealed this 10th day of December, A. D. 1940.

Henry Van Arsdale,
Acting Commissioner of Patents.
